UNITED STATES PATENT OFFICE

CLIFFORD NORTON, OF SOUTH ORANGE, NEW JERSEY, ASSIGNOR, BY MESNE ASSIGNMENTS, TO OTIS ELEVATOR COMPANY, A CORPORATION OF NEW JERSEY

MECHANISM FOR OPERATING ELEVATOR DOORS

Application filed August 31, 1927. Serial No. 216,588.

This invention relates to improvements in controlling mechanism for simultaneously controlling elevator car doors and landing doors.

- 5 It is among the primary objects of the invention to provide a rugged construction in which the parts are adequately supported either on the elevator car or on the wall of the shaft.
- 10 One primary object of the invention is to make use of one power motor with separate actuating mechanisms for transmitting power from the motor to the car door and landing doors respectively so that when desired one 15 of the doors may be caused to open or close in advance of the other.

Another of the main objects of the present invention is to provide separate power-operated mechanisms for the car gate or door 20 and for the landing gates or doors by which they will be held in either open or closed position until they are positively moved by the power means, the preferred construction including an irreversible power-transmitting 25 mechanism for maintaining the doors in such positions.

It is a further object of the invention to provide an apparatus which is superior in its 20 operation to those previously constructed due to the use of a transmitting mechanism constructed to cause the initial and final movements of the door to be relatively slow whereas all movements of the doors in the intermediate stages will be at relatively high 35 speed.

It is a still further object to provide door or gate moving mechanism which is preferably moved by power but which, when desired, may be disconnected from the power 40 mechanism and moved by hand.

The combined car gate and landing door operating mechanism of my invention comprises in its preferable form an organization the principal parts of which are as follows:

45 An electric motor mounted on the car in any suitable position drives, preferably through an irreversible gear, a suitable shaft. Flexible members or chains two in number at least are suitably connected at one end of 50 each chain to said shaft in such manner that

by rotation in one direction of the shaft the chains, cords or similar device will be wound up or shortened, while rotation of the shaft by rotation of the motor in the opposite direction will extend or lengthen said cords or chains. The car gate on the car is provided with an operating mechanism embodying as one of its members a device preferably in the form of a lever of bell crank form having one 55 arm engaged with the gate or an operating member thereof and having its other arm connected with one end of one of said cords or chains. Also mounted on the car is an actuating member adapted when the car is at the landing to engage and move landing door 60 operating mechanism of any suitable character, a member of which is in position to be engaged by said actuating member. Said member of the landing door operating devices is preferably in the form of a bell crank 65 one arm of which is engaged or adapted to be engaged by the actuating member on the car while the other arm is tied to devices for moving the landing door. The actuating member on the car through which power is applied 70 to move the landing door is suitably connected with one end of the other of the two cords or chains the other end of which is wound up or released by rotation of the shaft, and said actuating member preferably comprises a cam 75 member adapted to be projected or moved when the car is at the landing by the operation of the cord or chain attached to it. When so projected or moved it engages the member 80 of the door operating mechanism fixed in position upon the landing to be so engaged when the car is at the landing.

85 Springs may be applied to produce a closing movement of the gate and door when the motor is reversed to slacken the cords or chains. The irreversible gear in the driving 90 connections of the motor holds the parts in position when the power is turned off. A cam or drum specially shaped to give an increased accelerating and decelerating movement to the door and gate at certain stages 95 and upon which the chains or cords are wound also forms a part of the apparatus in its preferred construction. Suitable circuit closing or controlling means for controlling 100

the motor form of necessity a part of the apparatus which also embodies other parts and devices as more particularly hereinafter described.

5 The invention consists in the combinations of devices and constructions of apparatus as hereinafter more particularly described and claimed whereby the above and other objects are secured.

10 Fig. 1 is a front elevation of an elevator car equipped with my invention.

Fig. 2 is a side elevation of the elevator car and a portion of the landing.

15 Fig. 3 is a front elevational view of a portion of the door controlling mechanism mounted upon the elevator car.

Fig. 4 is a similar view taken at right angles to Fig. 3.

Fig. 11 is a section on the line 11—11 of Fig. 4; and

35 Fig. 12 is a similar view with additional parts in section and showing the elements moved to different positions.

Fig. 13 is a diagrammatic illustration of the electric circuits employed.

40 In prior door operating devices it has been proposed to move both the car door and landing door by using the same actuating mechanism for both, the car door and landing door being interengaged, usually by means of a channel and pin, so that they are moved together. These devices are objectionable because the interengaging parts cannot be adequately supported, tending to become loose and noisy, and also because the doors must

45 always be moved entirely simultaneously.

It is proposed to overcome all the objectionable features in such prior devices by means of the mechanism described and claimed herein.

55 According to the present invention it is proposed to mount a motor directly upon the elevator car and from this one motor to move the car door or gate and the corresponding landing door or gate near which

60 the elevator has been stopped. To this end the elevator car 14 is provided with an electric motor 16 mounted upon the superstructure 18 of the elevator.

65 The motor 16 has separate connections for operating the car gate 20 and any one of the

landing gates 22. A driving shaft 23, 24 operated by the motor is provided with any desired type of universal connection 25 for rotating the worm gear 26. This gear meshes with the worm nut 28 mounted in housing 29 and supported on the shaft section 30 connected through the clutch mechanism 32 with the transverse driving shaft 34.

The motor 16 is provided with a usual 75 brake mechanism 36 for slowing down the rotation of the motor after the supply of electric current has been cut off. The brake mechanism 36 includes the friction brake bands 38 normally pressed into engagement with the rotatable brake drum 39 by means of the coil springs 40. The brakes are released from the brake drum by means of the brake release arm 42 operatively connected with the solenoid 44 energized and de-energized with the energization or de-energization of the motor 16, as will be explained more fully below in connection with Fig. 13. The elevator car gate 20 in the present instance is shown as of the collapsible type suitably supported by rollers upon the track 48 carried by the elevator car. While this type of gate is preferred it will be understood that any usual or preferred type of car gate or door may be employed and that the term "gate" herein used for convenience is intended to indicate any type of door or gate which is desired.

The operating mechanism for moving the gate 20 comprises in the present instance an elongated lever 50 pivoted upon the elevator superstructure as indicated at 52. This lever is formed with or has secured thereto angular extensions 53 and 54, the former being connected to the dashpot 55 and the latter being connected by means of a flexible chain or the like, 56, with an eccentric drum 58 carried by the main operating shaft 34. The flexible member 56 is secured to the drum member 58 at a point 60 close to the axis of rotation of the drum. It will be understood that the shaft 34 and drum 58 will rotate in a counter-clockwise direction as viewed in Fig. 3 for the purpose of opening the door thus causing the chain 56 to be moved slowly at first, then with increasing speed until the extended portion of the cam 58 has passed beyond the axis of the shaft 34, after which the speed of movement of the flexible element 56 and gate 20 will be decreased up to the point of the open gate position of the cam, as indicated in dotted lines in Fig. 3.

It is desired to have the car gate close under power other than that supplied by the motor 16, for example spring power, and to this end there is provided a relatively strong tension spring 62 connected by means of the chain 64 to a pivoted arm 66 having a hub portion mounted loosely upon the shaft 52 and formed with an end projection 68 capable of engagement circumferentially with

the lug 70 carried by the shaft 52. Rotation of the arm 66 in a clockwise direction as viewed in Fig. 9, will accordingly cause the lug 68 to engage the lug 70 and rotate the shaft 52 in a clockwise direction, under the influence of the spring 62, to close the door. The arm 66 is free, however, to be moved in the opposite direction without affecting the position of the shaft 52, the lugs parting as indicated in Fig. 10.

A cylindrical hub portion of the lever 66 is also preferably formed with a radial projection 72 constructed to be engaged by the pivoted latch 74 formed with a retaining lug 75 for retaining the lever 66 in the position it assumes when the door is substantially in its open position. The latch 74 and lug 72 thus constitute, when operated, a mechanism for preventing the spring 62 from functioning to close the gate 20. The latch 74 is desirably operated simultaneously with the clutch mechanism 32 and is accordingly formed with an extension 76 engageable with a portion of the clutch operating mechanism as appears more fully below.

The landing doors 22 may be of any desired construction, those illustrated herein being of the usual three unit sliding type supported upon suitable hangers mounted in the elevator shaft. The doors 22 are shown as operated by means of the toggle levers 78, 78a, 78b which are capable of being operated either manually or by power. The power operating mechanism includes a bell crank lever 80 pivoted in the elevator shaft and connected by means of links 81 and 82 to a bracket 79 mounted on one of the toggle levers 78a as indicated at 84. The adjacent ends of the links 81 and 82 are shown as supported by means of a lever 85 pivoted to a suitable support in the elevator shaft, one end of the lever 85 operatively connecting, through the piston rod 86, with the dashpot checking mechanism 88 of any preferred construction for checking the opening movement of the door.

Since it is preferred to close the door by means of spring mechanism this may be accomplished by means of the compression spring 90 mounted within the spring casing 92 pivotally supported in the elevator shaft, the rod 93 of the spring mechanism being pivotally connected to the toggle link 78a as indicated at 94. The lower portion of the spring casing 92 is formed as a dashpot mechanism for checking the closing movement of the door under the influence of the spring 90.

There is also preferably employed any usual type of interlock switch as indicated diagrammatically at 95 which interlock contacts with the toggle links 78 to open the hoisting motor controlling circuit when the toggle links are in any except their locked position as shown in full lines in Fig. 5.

The interlock switch disclosed is of the

type disclosed and claimed in my prior Patent No. 1,562,183, patented Nov. 17, 1925.

The power actuating mechanism for the doors 22, in particular the bell crank lever 80 thereof, (see Fig. 2) may be actuated by means of the cam member 96 movably supported upon the frame of the elevator car by means of the links 98 and actuated by means of the flexible member 102. The flexible member 102, after passing over the pulley 103, extends to and is secured to the eccentric drum 100 which is securely fastened on the transverse power operated shaft 34 for rotation therewith. The flexible member 102 is attached to this drum at a point 104 near the axis of rotation of the drum and shaft. The drum is formed with a projecting portion for receiving the flexible element 102 to cause the car door to be moved rapidly during the intermediate stages of its opening movement and to permit the door to be moved more rapidly through the intermediate points of its closing movements under the influence of its closing spring.

The clutch member 32 is provided for the purpose of freeing the power shaft section 30 from the main operating shaft 34 and cams 58 and 100. The clutch 32 is shown as operated by means of the foot pedal 106 connected with the lever 107 which in turn is connected with the flexible element 108 which, after passing over suitable guide pulleys, is attached through the rod 109 to the lever 110 pivotally mounted upon the frame of the car. The lever 110 is in turn connected to the link 111 pivoted to the clutch operating bell crank lever 112 pivotally supported upon the frame adjacent the clutch mechanism 32. The yoke portion 113 of the bell crank 112 is formed for engagement with the clutch collar 114 for moving the clutch to or from operative position. The clutch is normally held in engaged position by means of the tension spring 116 as shown for example in Fig. 4. The rod 109 is provided with an enlarged nut 118 adjustably mounted thereon and formed for engagement with the end 76 of the latch 74 so that, upon the operation of the clutch to release the same, the latch 74 is lowered into position to engage the lug 72 for the purpose described above.

It is desirable that the motor circuit be opened when the door mechanism has reached the end of its movement in either direction. To this end the shaft 34 is provided with the rotatable disk 120 securely fastened to this shaft and carrying adjustable plates 121 and 122 formed with projecting lugs 123 and 124 respectively. Each of the lugs 123 and 124 is designed to be moved into engagement with one of the spring-pressed pivoted levers 125 and 126, for opening the circuits of the circuit breakers 127 and 128. These circuit breakers are identical in construction and include the movable con-

ductors 129 and 130 normally spring-pressed into engagement as seen at the righthand of Fig. 12 but separable by means of the insulating plate 132, as shown at the lefthand in Fig. 12. The plates 121 and 122 may be 5 adjustably mounted upon the disk 120 and the supporting rods for the insulating plates 132 may be adjustably connected to the levers 125 and 126 so as to accurately fix the time 10 of opening the circuits with respect to the movement of the doors. It will be understood that one of the circuits, for example that indicated at 127a, controlling the door opening circuit for the motor, will be opened 15 when the door has reached substantially open position and that the other circuit, for example 128a, will be opened when the door has reached substantially closed position, the opening of these circuits being responsive to 20 the rotation of the main operating shaft 34.

Referring now to Fig. 13 wherein there is disclosed a complete diagrammatic view of the electric conducting circuits which may be used in connection with this apparatus, 25 the main power circuits for the hoisting motor and door controlling motor are indicated in heavy lines and the auxiliary circuits in lighter lines. Referring to the details of this figure, the hoisting motor 134 is 30 normally controlled by means of the shiftable hoisting controller 135 as is usual in elevator controls. The controller 135 is provided with conductors 136 and 137 capable of engagement with one upper and one lower 35 contact 138a, 138b, 138c and 138d. The conductors 136 and 137 are arranged in permanent conducting relation to the main power lines extending to and from the hoisting motor 134.

40 Current is supplied to the terminals 138b and 138d through the main power lines *a*, *b* and *c* leading from one power line, termed the positive for convenience. Current is supplied from the other or negative power 45 line to the remaining terminals 138a and 138c through the conductors *d*, *e* and *f*.

It will thus be seen that movement of the hoisting controller 135 to the right or to the left causes the current to pass through the 50 hoisting motor in either of two directions to move the elevator car either up or down as desired. The controller 135 is formed with projections 140 engageable with the conductor 142 for moving the latter into engagement with the conductor 143 when the controller is moved into either of its operative 55 positions.

The purpose of the make and break contact switch 142, 143 is to energize or de-energize the relay 144 provided with an armature 144a carrying the conducting plates 145 and 146 capable of bridging either the upper terminals 147 or the lower terminals 148. Current is supplied to the relay 144 through 60 the branch conductor *g* leading from the

main power line *f* through the relay 144, to the switch plate 143. The armature 144a may be returned to its lower or de-energized condition by gravity, assisted if desired by means of a spring. 70

It is often considered desirable to be able to close the doors in advance of the starting of the car. This may be accomplished by means of the auxiliary circuit *m* which forms a shunt around the automatic switch 142, 143. The circuit *m* may include a manual switch 141 and a floor operated switch 141a in circuit therewith closed in the usual manner when the elevator car is substantially at a landing. This circuit *m* will thus permit the doors to be closed through the actuation of the relay 144 at any time the car is even with a floor. 75

The contacts 147 and 148 form parts of circuits leading respectively to the door closing and door opening relays 150 and 152 provided with armatures 153 and 154 respectively. The armature 153 carries terminals 155 and 156 insulated from one another and from the armature and movable into engagement with the terminals 157 and 158 for the purpose of operating the door moving motor 16a in one direction. 80

The armature 153, when energized, also closes contacts 160 and 162 leading respectively to the electromagnet 164 and the brake releasing relay 44a. The electromagnet 164 serves, when energized, to open the switch 170 to cause the current to pass through the resistance 172 so that upon the operation of the motor in a direction to permit the door to close, the current supplied to the motor will be considerably reduced as will be readily understood. The relay 44a is provided for the purpose of releasing the brake 36a from the door motor 16a, constructed as shown more particularly in Fig. 8. 95

The armature 154 carries contacts similar to 155 and 156 but reversed as to their positions so that when the relay 152 is energized current is supplied to the motor 16a in the reverse direction so as to cause the doors or gates to be opened. The armature 154 carries with it the conductor 157 which closes the circuit to the relay 44a to release the door motor brake 36a. 100

The armatures 154 and 156 are preferably connected for reverse movements as, for example, by means of the lever 174. This lever may be normally maintained in a neutral position with both armatures in inoperative position by any desired means, for example the spring 176. 110

The limit switches 127 and 128 are illustrated diagrammatically in Fig. 13 at 127a and 128a respectively, the same being shown as operated by the rotary members 120a to open the corresponding circuits when the door has reached the limit of its movement in either direction. 125

It is believed the circuits to the various elements will be readily understood from the above description without further elaboration, the functions of the various parts being

5 further explained in connection with the following description of the operation of the mechanism.

The operation of the electric circuit controls for the mechanism herein disclosed may 10 be briefly described as follows: In normal operation when the hoisting controller is moved to neutral, the relay 144 is de-energized thus permitting the armature 144a to descend. This energizes relay 152 and supplies electric current to the door moving motor 16 in a direction to open the door, the 15 brake relay 44a being released to permit movement of the door moving motor. As the door reaches substantially open position the 20 limit switch 127a is opened thus de-energizing the door opening solenoid and permitting the motor 16 to come to rest. The door moving motor is energized for operating the same in the reverse direction upon the movement 25 of the controller 135 either to the right or to the left, either of which movements would cause the contacts 147 to be bridged and the door closing relay 150 to be operated. The actuation of the relay 150 not only supplies electric current to the door moving motor 16a for moving the motor in a closing direction, but this relay 150 simultaneously 30 actuates the electromagnet 164 to automatically throw in the resistance 172 and also actuates the relay 44a to release the motor brake. The limit switch 128a is actuated to open the circuit automatically when the door reaches substantially its closed position.

The operation of the mechanical door moving mechanism herein disclosed is as follows: Upon the actuation of the door moving motor 16 in a direction to rotate the main driving shaft 34 in a counter-clockwise direction, as viewed in Figs. 1 and 3, the door moving elements 56 and 102 are caused to be wound upon the respective drums 58 and 100. Due to the differential shape of the drums 58 and 100 the car gate 20 and shaft door 22 are caused to move in an open direction slowly at first, then with increased speed, and finally at relatively slow speed, the final operations of both the opening and closing movements of the door preferably being checked by means of the dashpots as shown.

55 Both the car door or gate and landing door are caused to remain open due to the resistance inherent in the worm drive mechanism used to operate the driving shaft 34. At this time the door closing springs 62 and 90 are tensioned but are ineffective to cause the closing of the doors. Upon the reversal of the door moving motor 16 to cause the same to move in a door closing direction, the springs 62 and 90 are permitted to become effective and both doors are closed under the

influence of these springs, the motor 16 during this operation serving merely to reverse the rotation of the shaft 34 so as to permit the springs to be effective.

If for any reason it is desired to move the 70 car gate or door or landing doors by hand this may be accomplished by depressing the foot lever 106 thus releasing the main shaft 34 from the driving motor by opening the clutch mechanism 32. The depressing of the 75 foot pedal 106 also releases the shaft 34 from the influence of the spring 62 after the car gate is in open position, since this operation causes the hook 74 to engage and hold the hub supporting the arm 66 in an inoperative condition.

It will thus be seen that this invention provides complete separate actuating mechanism for car doors and landing doors operated from one motor mounted upon the car. The 85 operation is automatic throughout and is capable of giving as high speed operation as is consistent with safety.

It will be understood that the invention is not limited to the use of the particular eccentric drums 58 and 100 shown herein, but that the shape of these members may be varied for different conditions of use and in fact might be displaced by simple lever arms which would fulfill some of the functions of the cams 58 and 100. In other words the points of attachment of the chains of flexible members to the rotatable shaft may be such that these members will be wound upon the eccentric drum shown or on other drums 95 which have constantly increasing radii or they might with some degree of satisfaction be secured to arms having substantially constant radii. Different speeds of operation can thus be accomplished by substituting different drums for either or both of the drums 100 on the shaft 34.

The terms "door" and "gate" are used in this application in their broad sense of meaning any closure for an elevator car or shaft.

Having now described my invention, I claim:

1. In an apparatus for operating elevator doors, the combination of an electric motor on the car, a car door, actuating mechanism for the car door directly connected with the said motor to cause said door to be opened, a landing door, actuating mechanism therefor on the car connected to said motor and projectable across the space between the car 115 and landing to open the landing door, an irreversible gear between said actuating mechanisms and the electric motor, means connected with the car door and other means connected with the landing door in which power is stored in the opening operation under the action of the electric motor, said stored power being restrained against closing the doors by the irreversible gear and means for reversing the direction of rotation 120 125 130

of said electric motor to permit the landing door and car door to close through the reversal of the gear by the action of the motor.

2. The combination with an elevator shaft door and an elevator car, of an electric motor on the car, a flexible member operatively connected to said door, means driven by the motor for winding up said flexible member for the door opening operation and including an irreversible gear, a spring in which power is stored in the opening operation for said door and means for reversing the electrical operation of said motor to reverse the gear to withdraw the obstruction of said gear to the closing of said door.

3. In combination with a movable elevator landing door and an elevator car, a motor carried by said car, mechanism for operating said door including a lever pivoted for movement in a plane transverse to the plane of movement of said door, and door moving means actuated by said motor and movable into engagement with said lever for moving said door.

25 4. In combination with a movable elevator landing door and an elevator car, a motor carried by said car, means operatively connected with said door for moving the same and including a door operating member mounted adjacent said door and having a portion movable toward and away from the plane of movement of said door, a cam movably mounted on said car for movement toward and away from the plane of movement of said door and engageable with said door operating member for moving the latter and means operatively connected with said motor for moving said cam and door.

40 5. In combination, an elevator car, a movable door movable to position to permit access to said car, a motor carried by said car, a rotatable eccentric drum on the car operatively connected with said motor to be rotated a portion of one revolution thereby, said drum including engagement portions of different radii and door actuating devices operatively connected with said door and coacting with said engagement portions to be moved to fully open position during the movement of said drum through a portion of one revolution, the engagement portions of said drum having smaller radii being effective during the initial and final stages of movement of the opening door.

45 6. In combination, an elevator car, movable car and landing doors movable to position to permit access to said car, a motor carried by said car, separate eccentric drums operatively connected with said motor to be driven thereby, and door actuating devices each operatively connected with one of said doors and each coacting with the eccentric portion of one of said drums to be moved thereby and by said motor.

55 7. In combination, an elevator car, a mov-

able door, a rotatable drum formed with an eccentric supporting surface arranged in a single plane and a flexible member operatively connected with said door and connected to bear upon said supporting surface for moving said door at varying speeds during uniform rotation of said drum.

8. In combination, an elevator car, movable doors movable to position to permit access to said car, individual rotatable eccentric cams, each formed with a supporting surface having varying radii, flexible members each operatively connected with one of said doors and connected to be wound upon one of said supporting surfaces for moving said doors at predetermined varying speeds.

9. In combination, an elevator car, movable doors movable to permit access to said car, a plurality of rotatable elements carried by said car, a plurality of flexible elements each operatively associated with different ones of said rotatable elements, and means for operatively connecting each of said flexible elements with one of said doors for moving the same.

10. In combination, an elevator car, a movable gate thereon, a movable landing door, a motor, a rotatable shaft driven by said motor, and separate means associated with said shaft and with said elevator gate and landing door respectively for transmitting power from said shaft to said gate and door.

11. In combination, an elevator car, a movable door, a power motor, means for operatively connecting said motor with said door for opening the same, and means for disconnecting said motor from said door to permit the latter to be opened by hand, spring means for closing said door and manually controlled means for rendering said spring means inoperative at will.

12. In combination, an elevator car, a movable door, a power motor, means for operatively connecting said motor with said door for opening the same, and means for disconnecting said motor from said door to permit the latter to be opened by hand, spring means for closing said door and manually controlled means for rendering said spring means inoperative at will, said last-named means being actuated simultaneously with the disconnecting of said motor from said door.

13. In combination, an elevator car, a movable car door, movable shaft doors, a motor mounted on said car, means for transmitting power from said motor simultaneously to said car door and to one of said shaft doors, said means including eccentric cam means, and manually controlled mechanism for disconnecting said motor from said eccentric cam means.

14. In combination, an elevator car, a motor carried thereby, a car door, landing doors, mechanism for operating said car door

and mechanism for operating said landing doors, separate means for transmitting motion from said motor to said mechanisms for opening said doors only, and additional means for closing said doors.

15. In combination, an elevator car, a movable door for permitting access thereto, a motor on said car, means for transmitting power from said motor to said door for opening the same, said means including irreversible power transmitting devices, additional means for closing said door, and means for automatically controlling said motor to cause the opening of said door and to permit the closing of said door.

16. In combination, an elevator car, a movable door for permitting access thereto, a motor on said car, means for transmitting power from said motor to said door for opening the same, said means including irreversible power transmitting devices, additional means for closing said door, and means for automatically controlling said motor to cause the opening of said door and to permit the closing of said door and means for de-energizing said motor when said door has reached substantially the end of its path of movement.

17. In combination, an elevator car, a movable door for permitting access thereto, an electric motor on said car, means for transmitting power from said motor to said door for opening the same, said means including irreversible power transmitting devices, spring means acting upon the door for closing the same, electric power circuits for said motor, automatic circuit controllers for said circuits, and means for reducing the current supplied to said motor when said door is being closed by said spring means.

18. A combined car gate and landing door operating mechanism for elevators comprising in combination an electric motor mounted on the car, a car gate operating member, a landing door at each landing, operating means therefor including a member mounted in the elevator shaft, an actuating member therefor mounted on the car and adapted to engage said member to move the landing door when the car is at the landing and flexible elements both connected at one end with the electric motor and connected respectively at their opposite ends with the car gate operating member and with the actuating member which engages said member of the landing door operating means.

19. A combined car gate and landing door operating mechanism for elevators comprising in combination an electric motor mounted on the car, a car gate operating lever suitably connected with the gate, a landing door at each landing having a fixedly mounted operating lever fixedly mounted in the elevator shaft, an actuating member therefor on the car adapted to engage said lever for moving

the landing door when the car is at the landing and flexible elements both connected at one end with the electric motor and adapted to be wound up thereby and connected respectively at their opposite ends with said car gate operating lever and with the member on the car which actuates the landing door operating lever.

20. An elevator car gate and landing door operating apparatus comprising in combination an electric motor mounted on the car, a main operating shaft driven thereby, a car gate operating lever mounted on the car, a landing door at each landing and operating mechanism therefor at each landing including a bell crank lever fixedly mounted in the elevator shaft, an actuating cam member on the car adapted to engage and operate said bell crank lever and a pair of flexible actuating members both secured at one end to the said main operating shaft and at their other ends connected respectively with said car gate operating lever and with said actuating cam member for the landing door.

21. A combined car gate and landing door operating mechanism for elevators comprising in combination an electric motor mounted on the car, a pivoted car gate operating member, a landing door at each landing, operating means therefor including a fixedly pivoted member mounted in the elevator shaft, an actuating member therefor mounted on the car and adapted to engage said pivoted member to move the landing door when the car is at the landing and flexible elements both connected at one end with the electric motor and connected respectively at their opposite ends with the pivoted car gate operating member and with the actuating member which engages said pivoted member of the landing door operating means.

22. In combination with a movable elevator landing door and an elevator car provided with an opening to admit passengers, a motor carried by said car, mechanism for operating said door including an operating member on the car positioned adjacent one side of said car and formed with a portion movable toward and away from the face of said car provided with said opening for passengers for applying door opening power thereto, said mechanism including a cooperating member in the elevator shaft formed with a portion movable toward and away from the plane of said movable door, means for operatively connecting said first-named member with said motor for operation thereby and means for connecting said second-named member with said door for moving the latter.

23. In combination with a movable elevator formed with a face portion through which passengers may enter said elevator, a door opening motor, a movable landing door, door operating mechanism including a portion movable transversely with respect to the

plane of the face of said elevator during door movement, a power applying member operatively associated with said motor and constructed for coaction with the said movable portion of said door operating mechanism for applying door opening power to the latter, said power applying member being movable transversely with respect to the plane of the face of said elevator during the application of door opening power to said door operating mechanism.

24. In combination with a movable elevator landing door, a door operating lever associated with said door and pivotally mounted for movement in a plane extending longitudinally with respect to said door, a second lever pivotally supported for movement in a plane substantially at right angles to the plane of movement of said first named lever, means for applying power to said second lever and means for transmitting power from said second lever to said door operating lever.

25. An elevator door control comprising a pressure-actuated door-opener installed in proximity to the door, a pressure-imparting element carried by the car and operative upon said door-opener, and a cam to impart a predetermined movement to said element.

26. An elevator door control comprising a pressure-actuated door-opener installed in proximity to the door, a pressure-imparting element carried by the car and operative upon said door-opener, a cam to impart a predetermined movement to said element, and a motor to operate said cam controlled by the movements of the car control.

27. An elevator door control comprising a pressure-actuated door-opener installed in proximity to the door, a pressure-imparting element carried by the car and operative upon said door-opener, and a cam to impart a predetermined movement to said element, the characteristics of said cam being to render the terminal portions of such movement gradual.

28. An elevator door control comprising a pressure-actuated door-opener installed in proximity to the door, a pressure-imparting element carried by the car and operative upon said door-opener, a cam to impart a predetermined movement to said element, a motor to operate said cam, and means carried by the cam to stop the motor after said element has received its predetermined movement.

Signed at New York, in the county of New York and State of New York, Aug. 30, A. D. 1927.

CLIFFORD NORTON.
